UNITED STATES PATENT OFFICE.

JOHN G. BLESSING, OF CHICAGO, ILLINOIS, ASSIGNOR; BY MESNE ASSIGNMENTS, TO AUTOMATIC ELECTRIC INC., OF CHICAGO, ILLINOIS, A CORPORATION OF DELAWARE.

IMPULSE-TRANSMITTING DEVICE.

Application filed June 7, 1924. Serial No. 718,480.

The present invention relates in general to impulse transmitting devices for use at substations of automatic telephone systems. Impulse transmitting devices of this type are commonly known as calling devices, and the impulse transmitting device of the present invention will be hereinafter referred to as such.

The object of the present invention is to provide a calling device which is so arranged and constructed that when any one of a certain limited number of parties is to be called a single selective action on the part of the calling party suffices to enable the calling party to call the required party instead of having to effect a number of selective actions. Attempts have heretofore been made to devise and construct a calling device accomplishing this result, but the nearest approach, so far as applicant is aware, is the impulse transmitting device disclosed in Patent No. 1,306,829, issued to E. A. Mellinger June 17, 1919, in which a "setting up" operation followed by a single selective operation is required.

The invention will be more readily understood from the following description taken in connection with the accompanying drawings forming a part of this specification.

Referring now to the drawings, Fig. 1 shows a side elevation of the calling device with certain parts cut away.

Fig. 2 is a front view of the finger hole dial and the finger stops.

Fig. 3 is a diagrammatic view of the mechanism of the device.

Fig. 4 shows circuit connections between the device and substation apparatus provided with the usual calling device.

Fig. 5 is a cross-sectioned fragmentary view of certain parts.

Fig. 6 is a top view of the movable finger stop 11'.

Fig. 7 is a sectional view of Fig. 3 taken from dotted line C—C as seen when looking in the direction indicated by the arrows A—A.

Fig. 8 is a sectional view of Fig. 3 taken from dotted line C—C as seen when looking in the direction indicated by arrows B—B.

While Figs. 7 and 8 show the mechanism below and above line C—C, respectively, there is this difference—Figs. 7 and 8 show various parts positioned as they actually are

in the device and not diagrammatically as shown in Fig. 3.

Fig. 9 is a bottom view of Fig. 7.

Figs. 10, 11, 12, 13 and 14 show various details.

Referring now to Figs. 1, 3, 7 and 8, a tubular member 2 provided with a flange 4 is fixed to a base 1 by means of screws 3. These parts form the housing for the mechanism about to be described. In order to provide a framework for the mechanism two mounting plates 7 and 8 are provided which are connected together by three spacing members or posts 5. One of these posts is shown complete in Fig. 1, while all three posts and their particular location is clearly shown in Figs. 7 and 8. Each of these posts has a cut away portion provided with a round head machine screw 6 (see Figs. 1 and 7). When the mechanism is properly placed in the tubular housing 2 the screws 6 come into alignment with holes 9 in the tubular housing 2. These holes are slightly smaller than the largest part of the head of screws 6 and, as is evident in Fig. 1, when these screws are screwed outward they register with the holes 9 and in so doing lock the framework for the mechanism in place.

Heretofore in calling devices of the dial type the usual purpose of the dial has been to provide means for winding up a spring, which upon release of the dial, was rendered effective to operate an impulse cam a number of revolutions depending upon the degrees of forward rotation of the dial.

In the present case, however, the means for driving the impulse cam is in no way influenced by the finger hole dial, but instead movable finger stops are provided which are operated a definite distance, each time the device is operated, to cause the impulse cam to be driven a definite number of revolutions regardless of the digits of a called number.

The finger hole dial in the present case serves as a subscriber's number selecting device in that its degrees of rotation determines which operations of the impulse cam will be rendered ineffective.

Referring now to Figs. 3 and 5, the arrangement of the movable finger stops and the chain of gears connecting them with the impulse cam will be described.

Referring particularly to Fig. 5 it will be noted that the bar 56, its ends forming the

finger stops 11 and 11', has fixed to its lower side a gear 13. This gear is in the form of a cup in which is mounted a power spring 54, the outer end of which is fixed to the gear 13. An upward extending portion of plate 8 is provided with a lug 55 to which the inner end of spring 54 is fastened. A downwardly extending hub 107 fixed on the member 56 extends through plate 8, and serves as a shaft for member 56.

Gear 13 is permanently in mesh with the gear 14 of a gear unit comprising gears 14, 17, and ratchet disk 32. This unit is rotatably mounted on a downwardly extending shaft staked to bridge plate 16 as shown in Fig. 5. Gear 17 is permanently in mesh with a pinion 18, and a pawl and ratchet arrangement is provided, shown in Figs. 11 and 13, between pinion 18 and gear 19. Gear wheel 19 is in permanent mesh with a pinion 20 which is permanently fixed to shaft 58. Also fixed to this shaft is the impulse cam 39 and the worm wheel 63. The worm wheel is in permanent mesh with the governor assembly 21 which, as clearly shown in Fig. 8, is fixed to the plate 8 by means of a bracket 101, and screw 99 carried by a threaded member 100, which is staked to the plate 8. A hub having an arm 40 which is also fixed to the shaft 58 is provided for a purpose which will be hereinafter described. Before the gear 13 is placed down far enough to mesh with gear 14, and after the spring 54 is fixed in place, member 56 is rotated two or more revolutions in order to store a proper amount of tension in spring 54. A projection 108 on the bridge plate 16 is in the path of projections 43 and 43' preventing the unwinding of spring 54 and limiting the movement of member 56 in either direction to slightly less than one-half revolution, pin 43' engaging pin 108 in one case and pin 43 engaging pin 108 in the other case.

The gear ratio between gears 13 and 14 is such that when the bar 56 is rotated as far as it will go, gears 14 and 17 and ratchet disk 32 will be rotated slightly more than one complete revolution.

Referring now to Figs. 3 and 12, shaft 74 has fixed to it the L-shaped arm 75, the auxiliary disk 31, and a code disk assembly comprising a bank of twenty disks 30. Auxiliary disk 31 carries a pawl 33 and a tooth 62. Pawl 33 normally engages the tooth of ratchet disk 32, while a spring retaining pawl 37 mounted on plate 8 normally engages tooth 62. The twenty disks 30 (see Figs. 3, 4 and 12) are spaced an equal distance apart on shaft 74 by spacing members 45 and held in place by the nut 29. The rotation of any disk 30, independent of shaft 74, is positively prevented by the key or arm 75. As will be noted from observation of Fig. 3, the upper end of shaft 74 is considerably larger in diameter than its lower

end and is drilled out to receive a bushing 106, as shown in Fig. 7, and has for its axis the lower portion of shaft 105. Shaft 74 is pivoted and insulated at its lower end from plate 7 in the manner shown in Fig. 10, 70 wherein a bushing 70 is placed in an appropriate hole in plate 7 and the terminal 67' is held in place adjacent this bushing by means of machine screw 52. A washer 67' of insulating material is then placed on the screw 52 and the nut 68 is screwed in place.

During a forward rotation of members 56 through the medium of one of its finger stops gear 13 rotates gear unit comprising gears 14, 17 and ratchet disk 32 one complete revolution. Due to the ratchet connection between this unit, and the gears driving the impulse cam and governor, these latter mechanisms are not operated. The tension in spring 54 is, however, increased and when the finger stop is released the impulse cam is rotated a definite number of revolutions at a speed determined by the governor assembly. 90

Also due to the ratchet connection between the gear unit comprising gears 14, 17 and ratchet disk 32 and the code disk assembly, this assembly is not rotated during the setting movement of the finger stops, but rotates a complete revolution with the above gear unit when the finger stops are released. One of these disks is effective to operate springs for rendering certain operations of the impulse cam ineffective as will be subsequently explained. 100

As previously mentioned the dial serves to determine, by its degrees of rotation the number of operations of the impulse cam which are to be effective. As will be apparent from Figs. 3 and 5 the dial 12 is fixed to a shaft 22 which has also fixed to it a ratchet wheel 26. The dial is provided with a downwardly extending pin 15, and a spring 23 wound about the shaft 22 and having one end resting against a pin 42 fixed to plate 8 and the other end resting against a pin 35 on the hub of ratchet 26. This spring normally holds the pin 15 of dial 12 in the U-shaped part of finger stop 11', see Fig. 6. A bracket 88 carrying a shaft 89 is fixed to plate 7, as shown in Fig. 7. On this shaft is rotatably mounted a hub 90 carrying arms 25 and 97', which are soldered or welded together in any well known manner. A spring 38 links the arm 97' of the assembly to a member 53 fixed to the plate 7 and serves, under normal conditions, to maintain arm 25 in the position shown. A wall having the form of an inclined plane extends slightly less than half way around the ratchet wheel 26 and a roller 34 on arm 25, clearly shown in Fig. 7, is engaged by the lowest point of the incline when the dial and the ratchet wheel have been rotated 120 115 125 130 135 140 145 150 155 160 165 170 175 180 185 190 195 200

slightly less than one half revolution. It will be evident that by rotating the dial and the ratchet various distances, beyond one half revolution, the roller 34 will be raised by the incline and, as a result, arm 25 and bracket assembly 44, carrying springs 80, 61, 60 and 59 of the device, elevates these springs into operative relation with a disk of the code disk assembly, the disk selected being determined by the distance of the rotation of the dial.

A shaft 97 is provided which has fixed to it at its upper end a cam-like arm 50, and on the other end of this shaft is keyed a hub provided with a member 46 and a pawl 47. As clearly shown in Fig. 9 a spring 77 having its ends connected to plate 7 and pawl member 47, respectively, tends to rotate pawl 47 into engagement with teeth of ratchet wheel 26, and member 46 away from the path of rotation of the previously mentioned arm 40 on shaft 58. A pin 51 (see Fig. 3) on gear 13, however, normally engages arm 50 of shaft 97, and as the normal tension of the power spring 54 is much greater than that of spring 77, pawl 47 is normally held disengaged from the teeth of ratchet wheel 26, while arm 46 is normally held in the path of rotation of the previously mentioned rotatable arm 40 on shaft 58.

Minor details of the construction not brought out in the above description as they in no way effected the operation of the device will now be described. Mounted on the bottom side of plate 7 in the position shown in Fig. 9 is a terminal assembly 76 provided with three pairs of terminals (see Fig. 9), consisting of solder terminal 78, screw terminal 78', solder terminal 77, screw terminal 77', solder terminal 79, and screw terminal 79', respectively. These solder terminals are for making connections to various springs on the calling device, while the screw terminals are for connecting with conductors extending to substation apparatus.

An impulse spring and terminal assembly is also mounted on plate 7. This impulse spring and terminal assembly (see Figs. 7, 9 and 14) consists of a block of insulating material 125 fixed to plate 7 by means of screws. This insulation carries the impulse spring and terminal assembly the particular construction and arrangement of which may be seen in Fig. 14. Referring to Fig. 14, the insulation 125 and spring 66 are each provided with D-shaped holes. A machine screw is provided with an enlarged D-shaped key or portion adjacent its head. By means of this screw and its washer 127 and nut 128 spring 66 is firmly locked in place. Screw 126 is drilled out and threaded to receive screw 129, this screw acting in the capacity of a terminal and enabling connection to be made with the spring without

soldering. This arrangement is desirable as it enables a repairman to substitute new springs without the use of any tools other than a screwdriver. Spring 67, of course, is mounted in the same manner.

Referring now particularly to Figs. 2, 3 and 5, as previously described, the ratchet wheel 26 and finger hole dial 12 are fixed to a common shaft 23. From this it will be apparent that regardless of the degrees of rotation of dial 12 a like rotation of ratchet wheel 26 will take place. With this fact in mind particular attention is called to the arrangement of the finger holes on dial 12. As will be apparent, when the dial is operated from any finger hole located on the right of bar 56, stops 11 and 11', the finger stop 11 will be used, but when the dial is operated from any finger hole at the left of bar 56 stop 11' will be used. Now it should be noted that the first hole of the series at the right of stops 11 and 11' (the hole opposite the name Obergfell) is only a short distance from stop 11, a distance equal to an angular displacement of the dial of 8 degrees. As previously stated, finger stops 11 and 11' are operable slightly less than one-half revolution, 156 degrees. The first hole (opposite the name Martin) at the left of stops 11 and 11' is twice the distance away from stop 11' as is the hole (opposite the name Obergfell) nearest the stop 11. The axis of each hole of a series on either side of stops 11 and 11' are 16 degrees apart.

Now considering first the setting up operation of the device from the finger hole opposite the name Obergfell. The operator places a finger in this hole and operates the dial in a clockwise direction as far as it will go. When the dial has been rotated 8 degrees the finger engages finger stop 11 and since the stop can only be rotated 156 degrees the dial is rotated a total distance of 164 degrees. As soon as the dial has been rotated 156 degrees the lowest point of the inclined track or wall on ratchet wheel 26 (see Figs. 3 and 7) engages roller 37 of arm 25, but does not elevate it. The pitch of the incline on ratchet wheel 26 is such that the dial and ratchet wheel on rotating the next 8 degrees causes the incline on the ratchet wheel to move the roller 34 and arm 25 vertically one step or a sufficient distance to position the springs 60, 61 and 80, carried by bracket 44, into operative relation with the lowermost disk 30. This elevation of arm 25 from its normal position is equal to the distance between each of the disks 30 which are equal distances apart from each other. It will, therefore, be seen that 8 degrees of rotation will be required for elevating the springs from one disk to the next.

If the dial had been rotated from the finger hole opposite the name Lawson the dial would have been rotated the 164 degrees

plus 16 degrees, or a total of 180 degrees. Now, as previously described, only 8 degrees of rotation plus 156 degrees is required to elevate the arm 25 and the springs 60, 61, and 80 into operative relation with the first or lowermost disk 30. Therefore, if the dial is rotated 16 degrees more it will be evident that the arm 25 and springs 60, 61, and 80 will be elevated into operative relation with the third disk (counting the bottom disk as the first). If the dial had been operated from the hole opposite the name Harris it would have been operated 156° plus 8° plus $(9 \times 16^\circ)$ or a total of 300 degrees. Now subtracting the first 156° , these degrees being ineffective to elevate arm 25, leaves a remainder of 152 degrees each of which would be effective to lift the arm 25. Since 8 degrees are required to lift the springs 60, 61, and 80 from one disk to the next the said springs would in this case have been lifted into operative relation with the nineteenth disk or level. This may be determined by dividing the effective degrees, 152, by 8.

It will be recalled that the finger hole opposite the name Martin was 16 degrees away from finger stop 11'. If the dial is operated from this finger hole it will be evident that 16 degrees of the rotation of the dial will be effective, and as a result springs 60, 61, and 80 will be positioned opposite the second level or disk 30. Now if the dial had been operated from the finger hole opposite the name Matousek the effective rotation of the dial would equal to 16° plus $(9 \times 16^\circ)$ or a total of 160 degrees, causing the springs 60, 61 and 80 to be moved into operative relation with the twentieth level or disk 30. From the above it will be evident that by the manipulation of the dial from a particular finger hole a particular level or disk will be automatically selected.

Having described the mechanical structure of the calling device and the relationship between the two finger stops and the finger holes, a description of its operation will now be given, reference being had particularly to Figs. 2, 3 and 5. It will be assumed that the subscriber designated as Obergfell (see Fig. 2) is desired. The subscriber after removing his receiver places a finger in the hole opposite the name of the subscriber desired and rotates the finger hole dial in a clockwise direction as far as it will go. As soon as the finger has rotated the dial a short distance the finger engages stop 11 and carries this finger stop with it. When the finger stop has been rotated 156 degrees pin 43 engages fixed pin 108 and therefore cannot be rotated any further. As soon as the finger stop is moved from its normal position pin 51 disengages itself from arm 50. This permits shaft 97 to rotate under tension of spring 77 (see Fig. 9) until arm

46 moves out of range of arm 40, and arm 47 engages the ratchet teeth of ratchet wheel 26. The movement of arm 47 into engagement with teeth of ratchet wheel 26 does not prevent this wheel from being rotated in a clockwise direction, but instead locks it from rotation in the opposite direction. In the manner previously described springs 60, 61, and 80 are elevated into operative relation with the lowermost disk 30. Also, during the clockwise movement, gear 13, being fixed to bar 56, is rotated sufficient to rotate gear 14 a complete revolution. Due to ratchet disk 32 and pawl 33 the shaft 74, however, is not rotated. As previously pointed out ratchet tooth 62 and pawl 37 are provided to guard against any possible backward rotation of the shaft 74. Also, due to ratchet wheel 72 and pawl 73 (see Fig. 11), shaft 58 is not rotated.

Now, when the finger is removed from the finger hole dial, bar 56 in common with stops 11 and 11' returns to normal under tension of spring 54, and shaft 74 and the governor driving gear 19 are now rotated, the governor acting to regulate the speed of the mechanism in the usual manner. Since pinion 20 is fixed on shaft 58 this shaft also rotates causing cam 39 to open impulse springs 66 and 67 a plurality of times. As soon as pin 51, on bar 56, again engages arm 50 shaft 97 is again rotated back to normal, arm 47 disengaging from gear 26 and arm 46 again moving into the path of rotating arm 40. Arm 47 permits the finger hole dial 12 to restore to normal under tension of spring 22, while arm 46 prevents any overrun of the cam 39. The return to normal of the ratchet wheel 26 permits arm 25 and bracket 44 to restore to normal by tension stored up in spring 38 during the elevation of arm 25.

The normal position of dial 12 is determined by a leather covered pin 15 extending downward from the underside of the dial. This pin engages the U-shaped portion of stop 11' (Fig. 6).

The impulse springs 66 and 67 are operated 120 times by the cam 39, but due to circuits which will now be described, certain operations of springs 66 and 67 are rendered ineffective. Referring to Fig. 5, it should be noted that springs 66 and 67 are normally short-circuited by springs 60 and 61, and, as previously stated, the shaft 74 and its disks 30 rotate one revolution each time the dial is operated. Therefore, when the surface of cam 30 engages brush 59 the substation transmitter and receiver are short circuited, this short circuit extending by way of disk 30, brush 59, spring 60, springs of calling device C. D., transmitter T, receiver R and back to cam 30. At the same time the transmitter and receiver are short circuited spring 61 is engaged or lifted by cam 113

of disk 30 removing the short circuit from around springs 66 and 67 for sufficient time to render one operation of cam 39 effective, after which the springs 66 and 67 are again short circuited for a sufficient time to allow the switch under control of the first series of impulses to complete its maximum trunk hunting movement, after which cam 114 opens the short circuit from around the impulse springs. Cam 114 maintains the short circuit removed for a period sufficient to render five operations of the impulse springs effective after which they are again short circuited by springs 60 and 61. As soon as cam 115 engages spring 61 the short circuit around the impulse springs is again removed, this time for a sufficient time to render effective eight operations of the impulse springs. From this it will be evident that the number of the called subscriber is 158. Shortly after springs 60 and 61 have again short circuited springs 66 and 67, disk 30 upon rotating a little farther disengages itself from brush 59 thereby again removing the short circuit from around receiver R and transmitter T. The disk 30 continues to rotate until it has completed its revolution, but without effect other than to position itself in its normal position. The impulse cam 39 also continues to rotate until arm or bar 56, common to finger stops 11 and 11', restores to normal.

The calling device here shown and described illustrates the invention as used in a three digit system, but to use the same for a seven digit system merely requires the substitution of appropriate disks 30 in which case up to seven cam surfaces such as 113, 114, etc., would be distributed about the periphery of disk 30.

Having fully described and ascertained the various features of the invention, what is considered new and desired to have protected by Letters Patent will be pointed out in the appended claims.

What is claimed is:

1. In an impulse transmitting device, impulse springs, means for operating said springs a definite number of times each time the device is fully operated and restored to normal, means for short circuiting said springs, a plurality of means for removing said short circuit at different periods during the operation of said device, and means for determining which of said last means will be used.

2. In an impulse transmitting device, a pair of impulse springs, a power spring for operating said impulse springs, a plurality of cam surfaced disks each individual to a particular designation on said device, a pair of springs normally short circuiting said impulse springs, manually operated means for causing the elevation of said short circuiting means opposite a disk corresponding

its designation on said device, manually operated means operated incidental to the operation of said first manually operated means for storing power in said power spring to effect the operation of said impulse 70 springs and said disks.

3. In an impulse sending device of the dial type, means responsive to a single selective operation and release of the dial for causing the device to immediately transmit definite 75 and uniformly spaced series of impulses irrespective of the number of impulses in the respective series, and means responsive to another single selective operation of the dial for causing a like spaced different definite 80 series of impulses to be transmitted.

4. In an impulse sending device, manually operable means for preparing said device to transmit a series of impulses, and manually operable means for preventing the transmission of certain of said impulses so that those transmitted occur in groups in accordance with the distance of operation of said last means, said device so arranged that the operation of the first means is incidental to the 90 operation of the last means.

5. In combination with an impulse transmitting device, a casing, screws at points in the outer periphery of the device registering with holes in said casing, said holes being 95 slightly smaller than the largest portion of the heads of said screws permitting said screws to be turned outward to lock said device in said casing.

6. In an impulse transmitting device of the finger hole dial type, a plurality of diametrically disposed movable finger stops, said device operative responsive to a single operation thereof to transmit an impulse code comprising series of impulses, and means for causing the code transmitted to be jointly dependent on the finger hole and finger stop used.

7. In a code impulse sending device, a plurality of code determining elements, an element selecting means, means responsive to a single actuation of the device to cause said element selecting means to be positioned opposite a desired element, and means thereafter effective to rotate the element selected to effect the transmission of a desired code.

8. In an impulse sending device, a single dial and cooperating means for sending different codes of impulses by different operations of said dial, each operation transmitting a plurality of groups of impulses, said cooperating means including a plurality of impulse code determining elements and a setting device, said setting device automatically set opposite different impulse code determining elements by different operations of the dial.

9. In an impulse transmitting device, an impulse transmitter including pairs of normally closed contacts connected in multiple,

means for operating the device to cause a plurality of equally spaced operations of one pair of said contacts and for causing another pair of said contacts to be operated for variable periods.

10. In an impulse transmitting device, a finger hole dial, a plurality of disks, and means operated by the dial to select a disk, the disk selected being dependent on the extent of movement of the dial.

11. In an impulse transmitting device, a dial having a plurality of finger holes, a plurality of disks, there being a disk for each hole on the dial, and means operated by the dial effective to select the disk individual to the finger hole used in operating the dial.

12. In an impulse transmitting device for transmitting a plurality of impulse series each time it is operated, a pair of impulse springs, a cam for operating said springs a definite number of times each time the device is operated, a plurality of disks, and a single pair of contact springs having access to any one of said disks and cooperative with any disk with which it is associated to determine what operations of the impulse springs will be effective.

13. In an impulse transmitting device, a plurality of cam surfaced disks each individual to a particular designation on said device, a finger hole dial, means operated by said dial for causing the selection of any disk, impulse springs, means for operating said impulse springs a definite and invariable number of times irrespective of the disk selected and means cooperating with the selected disk for causing certain operations of said impulse springs to be ineffective.

14. In an impulse transmitter, a pair of normally closed impulse springs, a pair of normally closed shunt springs connected in multiple with said impulse springs, means for operating said impulse springs a definite number of times each time the transmitter is operated to transmit impulses, and means for periodically opening said shunt springs during the operation of said device to cause certain operations of the impulse springs to be effective.

15. In an impulse transmitting device of the dial type, impulse springs, means respon-

sive to a single selective operation of the dial for causing the impulse springs to be operated a definite number of times irrespective of the digit transmitted and means automatically effective periodically for causing the impulse springs to transmit impulses.

16. In an impulse transmitting device, impulse springs, a finger hole dial, a plurality of disks, means operated by the dial to select any one of said disks, a movable finger stop engaged by the finger of an operator and rotated incidental to the rotation of the dial, means operated by the finger stop for causing the operation of the impulse springs, other means operated by the stop preventing any movement of the dial after the stop has moved a definite distance and until the stop has been restored to its initial position, and means operated by the stop in a manner dependent on the disk selected for causing series of impulses to be transmitted before the dial is allowed to restore.

17. In an impulse transmitting device, an impulse transmitter having two pairs of normally closed contacts connected in multiple, automatic means for causing said pairs of contacts to be subsequently operated for intervals, the one pair of contacts transmitting a plurality of series of impulses, the number of impulses in each series being dependent on the intervals during which the other pair is operated.

18. In an impulse transmitting device, means for transmitting an excessive number of impulses responsive to a single actuation thereof and means for preventing certain selected series of said impulses from becoming effective.

19. In an impulse transmitter, a control circuit, a first and a second set of contacts, means for selectively varying the location of said first set of contacts, means for then operating both sets of contacts, and means variably influenced by said first contact set in a manner dependent on its location for also varying the effects produced by the operation of the second contact set.

In witness whereof, I hereunto subscribe my name this 3d day of June, A. D., 1924.

JOHN G. BLESSING.
